(57) **CLAIM**

The ornamental design for a display screen with graphical user interface, as shown and described.

DESCRIPTION

FIG. 1 is a front view of a display screen with graphical user interface showing my new design; and,

FIG. 2 is a front view of the display screen with graphical user interface of FIG. 1 shown on a device.

The broken line showing of the square, the selected alphabetical characters and the remainder of the display screen in FIGS. 1 and 2, and the remainder of the device having the display screen in FIG. 2, is for environmental purposes only and forms no part of the claimed design.

UNITED STATES PATENT AND TRADEMARK OFFICE
CERTIFICATE OF CORRECTION

PATENT NO. : D671,128 S
APPLICATION NO. : 29/384420
DATED : November 20, 2012
INVENTOR(S) : Frijlink et al.

Page 1 of 4

It is certified that error appears in the above-identified patent and that said Letters Patent is hereby corrected as shown below:

The Title page, showing the illustrative figures, should be deleted and substitute therefor the attached Title page.

In the Drawings:

Delete figs. 1 and 2 and substitute therefor the drawing sheets, consisting of figs. 1 and 2 as shown on the attached pages.

Signed and Sealed this
Thirteenth Day of August, 2013

Teresa Stanek Rea
Acting Director of the United States Patent and Trademark Office
